UNITED STATES PATENT OFFICE.

ALFRED D. ANTOINE, OF CHICAGO, AND ALBERT E. GEBERT, OF WILMETTE, ILLINOIS,
ASSIGNORS TO ADVANCE MACHINE COMPANY, OF CHICAGO, ILLINOIS, A CORPOR-
ATION OF ILLINOIS.

VAPOR BURNER.

Application filed August 21, 1922. Serial No. 583,147.

To all whom it may concern:

Be it known that we, ALFRED D. ANTOINE, residing at Chicago, and ALBERT E. GEBERT, residing at Wilmette, in the county of Cook 5 and State of Illinois, and both citizens of the United States, have invented certain new and useful Improvements in Vapor Burners, of which the following is a specification.

This invention relates to improvements in 10 vapor burners for effecting the combustion of liquid and fuel, particularly adapted though not necessarily limited in its use in the fire boxes of boilers or furnaces, and one of the objects of the invention is to provide 15 an improved device of this character embodying a water circulating system for generating steam and which water circulating system embodies a boiler or tank from which the water is supplied and into which 20 the hot water and vapor is delivered, the vapor or steam being then conveyed from the boiler and mixed with the fuel.

A further object is to provide an improved burner of this character embodying 25 improved means whereby all foreign particles such as sediment or the like will be removed from the water and confined so that they will not be carried with the vapor into the burner, thereby obviating the objectionable difficulty which has heretofore 30 generally been present in burners of this character, that is the clogging or fouling the parts of the device with the foreign matter, and which accumulation has heretofore 35 been difficult to remove.

To the attainment of these ends and the accomplishment of other new and useful objects as will appear, the invention consists in the features of novelty in substantially 40 the construction, combination and arrangement of the several parts hereinafter more fully described and claimed and shown in the accompanying drawings, illustrating this invention and in which—

45 Figure 1 is a view partly in front elevation and partly in section.

Figure 2 is a view taken on line 2—2 Figure 3.

50 Figure 3 is a top open view.

Figure 4 is a detail view taken on line 4—4 Figure 2.

Referring more particularly to the drawings, the numeral 10 designates generally a combustion chamber which may be of any

desired size and configuration, the rear wall 55 11 of which preferably curves outwardly and the bottom of the chamber is preferably provided adjacent the rear wall 11 with an opening 12, through which the products of combustion are delivered from the chamber. 60 If desired the top wall of the chamber may be provided with an opening 13 so as to promote combustion in the chamber.

The combustion chamber is provided with 65 a front wall 14 preferably of a size somewhat larger than the combustion chamber so that when the combustion chamber together with the associated parts of the burner are inserted into the fire box of a boiler or furnace, the front plate 14 will 70 serve as a closure for the boiler opening. This plate 14 is provided with a plurality of openings 15 therethrough for a purpose to be hereinafter set forth.

Associated with the combustion chamber 75 10 is a closed tank or boiler 16 of any desired size and configuration and is provided with an inlet opening 17 through which water is supplied to the boiler from any 80 suitable source such as the city supply. Encompassing this opening 17 is a valve seat 18 having a control valve 19 provided with a stem 20 arranged within the boiler.

This stem 20 is preferably mounted within a casing 21 and is adapted to be shifted longitudinally to shift the valve 19 to open and close the inlet 17, in any suitable manner preferably by means of a valve 22 connected with a lever 23 fulcrumed intermediate its ends as at 24, the free end of the lever being connected as at 25 with the stem 20.

The boiler is provided with an outlet 95 opening 26 for the water and connected with this outlet is a pipe 27 which discharges into a chamber 28, of any desired size and configuration. This chamber 28 may be formed as a casing or from a pipe section, and leading from the casing is a pipe 29. The casing or section 28 is preferably located in advance of the plate 14 to extend in a direction across the combustion chamber, and this casing or section 28 constitutes an initial heater for the water in a manner as will be hereinafter described.

The pipe 29 is preferably located exterior of the combustion chamber 10 and extends rearwardly along the outside of the cham-

ber to a point beyond the rear wall 11 and then extends transversely at 30 behind the wall and is closed by means of a suitable closure 31.

5 Connected with the pipe 30 to extend upwardly therefrom and in close proximity to the outer surface of the rear wall 11 of the chamber are a plurality of pipes 32 which discharge into a pipe or header 33 and 10 which header is connected as at 34 with a return pipe 35 that discharges into the boiler 16 as at 36 and at a point above the outlet opening 26. The water from the boiler will be discharged therefrom through 15 the outlet 26 and will circulate through pipe 27 section 28, pipe 29, pipe 30, pipes 32, header 33, and pipe 35 back to the boiler.

A burner 37 of any desired size and configuration is supported beneath the section 20 28 so that the products of combustion therefrom will be delivered against the section 28 to heat the same, thereby heating the water therein which will not only generate steam in the section 28 but will induce a circulation 25 of the water.

If desired, and in order to provide a short course of circulation of the water during the initial heating, a branch circuit may be provided and to that end a pipe section 38 may 30 be connected as at 39 with the pipe 29 depending therefrom and connected with a pipe 40 which in turn is connected with another pipe 41, the latter being connected with and discharging into the pipe 35 by means 35 of a suitable coupling 42 preferably arranged in close proximity to the boiler.

If desired, a cut off valve 43 may be provided in the branch circulation pipes 38, 40, 41, for cutting off said pipes after the water 40 has been initially heated to a sufficient temperature.

Arranged to discharge into the openings 15 in the plate 14 are fuel supply nozzles 43 and 44, one arranged in alignment with each 45 of the openings 15. These fuel supply nozzles are provided respectively with controlling valves 45 and 46 and the nozzles are preferably of different sizes and capacity.

The nozzles are adapted to be supplied 50 with fuel from any suitable source and in any suitable manner preferably by means of the pipes 47 and 48.

Leading from the boiler 16 preferably from a dome 49 thereof is a pipe 50 for conveying steam or vapor to the nozzles 43 and 44 preferably through a pipe 51 which is in communication with each of the nozzles 43 and 44 and in such a manner that the respective valves 45 and 46 will control both the 60 supply of fuel and the supply of vapor.

In operation, the initial heating burner 37, being supplied with fuel or gas from any suitable source, is lighted and allowed to burn a sufficient length of time to heat the 65 water in the section 28. If the branch circu-

lating system embodying the pipes 38, 40, and 41, is employed, the valve 43 is opened and there will be a local circulation of the water from the boiler through the opening 36 section 28, pipes 38, 40, 41, back to the 70 boiler through the opening 36.

If the local circulation system is not employed then the circulation will be made from the boiler through the opening 26, pipe 27, section 28, pipes 29, 30, 32, header 33, 75 pipe 35, back to the boiler through the opening 36.

After sufficient steam has been generated and delivered into boiler, either one or both of the valves 45 and 46 controlling the vapor 80 and fuel supply are adjusted or opened so that the steam will be delivered from the boiler 16 through the pipe 50 and branch pipe 51 to the nozzles 43 and 44. The fuel and vapor being mixed will be delivered through the openings 15 into the combustion chamber 10 where it is ignited by means of a pilot burner 52, the flame being delivered through the opening 53 into the combustion chamber. 90

The products of combustion in the combustion chamber will be delivered through the opening 12 in the bottom thereof and will pass around the sides of the combustion chamber to contact with the adjacent pipes 95 to heat the water therein. When the fuel is ignited in the combustion chamber the initial heating burner 37 may be shut off.

The boiler 16 is provided with an outlet valve 54 for the steam and the steam which is delivered through this valve may be conducted to any suitable point of use.

The valve 54 is so adjusted that it will not interfere with the desired steam pressure in the boiler or with the pressure or head of the water being supplied to the boiler through 105 the inlet 17.

If desired the boiler may be provided with a discharge outlet 55 leading from the bottom thereof and controlled by a suitable valve 56, for blowing off or cleaning out the sediment or foreign particles which will be separated from the water and will accumulate in the bottom of the boiler. The boiler may be provided with a chamber or recessed 110 portion 57 into which the sediment will settle. If desired a suitable gauge glass 58 may be provided for the boiler.

With this improved construction, the water circulating system and the provision of the boiler 16 serve as a means whereby the water will be purified before it is delivered to the fuel nozzles and all foreign particles such as sediment or the like which is carried by the water will be separated therefrom and discharged in the boiler, due to the fact that the water is converted into vapor after it leaves the boiler and before it is delivered back into the boiler, the vapor supply to the fuel nozzles being delivered thereto directly 120 125 130

from the boiler and after the vapor has been delivered into the boiler with the circulating water.

By the provisions of the nozzles 43 and 44 of different capacities, it will be manifest that under some conditions one nozzle will be all that will be required to supply sufficient fuel to the combustion chamber, under normal conditions, but with abnormal conditions, the additional or other burner may be brought into use, and the second burner may be of a capacity that its use only may be all that is necessary but it is, of course, to be understood that both nozzles may be employed at the same time thereby increasing the capacity or quantity of fuel whenever desired.

While the preferred form of the invention has been herein shown and described it is to be understood that various changes may be made in the details of construction and in the combination and arrangement of the several parts within the scope of the claims without departing from the spirit of this invention.

What is claimed as new is:

1. A vapor burner embodying a boiler having an inlet and an outlet for water, water circulating pipes, the ends of the pipe system being connected respectively with the said outlet and inlet, a supply nozzle, means whereby fuel may be supplied to the nozzle, a steam pipe leading from the boiler to the nozzle, a chamber into which the products of combustion are discharged, said chamber having openings through which the products of combustion may be discharged against the said water circulating pipes for inducing circulation therein and for generating steam to be delivered into the boiler, and a water supply inlet for the boiler.

2. A vapor burner embodying a boiler having an inlet and an outlet for water, water circulating pipes, the ends of the pipe system being connected respectively with the said outlet and inlet, a fuel supply nozzle, means whereby fuel may be supplied to the nozzle, a steam pipe leading from the boiler to the nozzle, a chamber into which the products of combustion are discharged, said chamber having openings through which the products of combustion may be discharged against the said water circulating pipes for inducing circulation therein and for generating steam to be delivered to the boiler, a water supply inlet for the boiler, and a steam outlet valve for the boiler.

3. A vapor burner embodying a boiler having an inlet and an outlet for water, water circulating pipes, the ends of the pipe system being connected respectively to the said outlet and inlet, a fuel nozzle, means whereby fuel may be supplied to the nozzle,

pipe for conducting steam from the boiler to the nozzle, a chamber into which the products of combustion are discharged, said chamber having openings through which the products of combustion may be directed against a portion of the said water circulating pipes for inducing circulation therein and for generating steam to be delivered to the boiler, a water supply inlet for the boiler, a sediment outlet leading from the boiler, and means for controlling the last said outlet.

4. A vapor burner embodying a boiler having an inlet and an outlet for water, a water circulating system, the ends of the system being connected respectively with the said outlet and inlet, a fuel supply nozzle, means whereby fuel may be supplied to the nozzle, a pipe for conducting steam from the boiler to the nozzle, a chamber into which the products of combustion are discharged, said chamber having openings through which the products of combustion may be directed against a portion of the said water circulating pipes for inducing circulation therein and for generating steam to be delivered into the boiler, a water supply inlet for the boiler, and means operating automatically to control the last recited inlet.

5. A vapor burner embodying a boiler having an inlet and an outlet for water, a water circulating system, the ends of the system being connected respectively with the said outlet and inlet, a fuel supply nozzle, means whereby fuel may be supplied to the nozzle, means for conducting steam from the boiler to the nozzle, means whereby the products of combustion may be directed against a portion of the said circulating system for inducing circulation therein and for generating steam to be delivered into the boiler, a water supply inlet for the boiler, a valve for controlling the last recited inlet, and a float within the boiler for controlling the said valve.

6. A vapor burner embodying a boiler having an inlet and an outlet for water, a water circulating pipe system, the ends of the pipe system being connected respectively with the said outlet and inlet, a fuel supply nozzle, means whereby fuel may be supplied to the nozzle, a pipe for conducting steam from the boiler to the nozzle, a chamber for receiving the products of combustion there being an opening in the wall of the chamber through which the products of combustion may be directed against a portion of the water circulating pipe system for inducing circulation therein and for generating steam to be delivered into the boiler, a water supply inlet for the boiler, an additional burner, and a branch in the water circulation pipe system adapted to be initially heated by the last recited burner.

7. A vapor burner embodying a water circulating pipe system, said system embodying a boiler to and from which the water circulates, a combustion chamber about which a portion of the system extends, said chamber having an opening in its wall adjacent a portion of the water circulating pipes, a fuel nozzle discharging into the said chamber, means for supplying fuel to the nozzle, means for supplying vapor from the boiler to the nozzle, a water supply inlet to the boiler, means operating automatically to control the said inlet, a sediment blow off for the boiler, and means for controlling the said blow off.

8. A vapor burner embodying a water circulating pipe system, said system embodying a boiler to and from which the water circulates, a combustion chamber about which a portion of the system extends, a fuel nozzle discharging into the said chamber, means for supplying fuel to the nozzle, said chamber having an opening in its wall adjacent the water circulating pipes, means for supplying vapor from the boiler to the nozzle, a water supply inlet to the boiler, means operating automatically to control the said inlet, a sediment blow off for the boiler, means for controlling the said blow off, and a valve controlled steam outlet leading from the boiler.

9. A vapor burner embodying a water circulating system, said system embodying a boiler, means for supplying water to the boiler, means operating automatically to control the last recited means, a combustion chamber about which a portion of the water circulating system extends, a plurality of fuel supply nozzles of different capacities and discharging into the said chamber, valves individual to the nozzles for controlling them, means for supplying steam from the boiler to the nozzles, and initial heating means for the water circulating system.

10. A vapor burner embodying a water circulating system, said system embodying a boiler, means for supplying water to the boiler, means operating automatically to control the last recited means, a combustion chamber about which a portion of the water circulating system extends, a plurality of fuel supply nozzles of different capacities and discharging into the said chamber, means individual to the nozzles for controlling them, means for supplying steam from the boiler to the nozzles, initial heating means for the water circulating system, and a branch circulating passage for the water and leading from the main circulating system, the water in the said branch being initially heated by the said initial heating means.

11. A vapor burner embodying a combustion chamber, a fuel supply nozzle dis-

charging thereinto, means for supplying fuel to the nozzle, a boiler having an outlet and an inlet for water, a water circulating system having its ends connected with the said outlet and inlet, said system embodying pipes disposed in close proximity to the walls of the combustion chamber, said chamber having an outlet through which the products of combustion pass to flow around the chamber and against the pipes, a steam pipe leading from the said boiler to the said nozzle, a water supply inlet to the boiler, and means for automatically controlling the last recited inlet.

12. A vapor burner embodying a combustion chamber, a fuel supply nozzle discharging thereinto, means for supplying fuel to the nozzle, a boiler having an outlet and an inlet for water, a water circulating system having its ends connected with the said outlet and inlet, said system embodying pipes disposed in close proximity to the walls of the combustion chamber, said chamber having an outlet through which the products of combustion pass to flow around the chamber and against the pipes, a steam pipe leading from said boiler to the said nozzle, a water supply inlet to the boiler, and means for automatically controlling the last recited inlet, a branch circulation passage in the pipe line for the water, and an initial heating burner disposed to direct the products of combustion therefrom against the said branch.

13. A vapor burner embodying a combustion chamber, a fuel supply nozzle discharging thereinto, means for supplying fuel to the nozzle, a boiler having an outlet and an inlet for water, a water circulating system having its ends connected with the said outlet and inlet, said system embodying pipes disposed in close proximity to the walls of the combustion chamber, said chamber having an outlet through which the products of combustion pass to flow around the chamber and against the pipes, a steam pipe leading from the said boiler to the said nozzle, a water supply inlet to the boiler, means for automatically controlling the last recited inlet, and an initial heating burner disposed to direct the products of combustion therefrom against a portion of the said pipes.

14. A vapor burner embodying a combustion chamber, a water circulation system embodying a boiler and a pipe system connected therewith, said pipes being disposed outside of and in close proximity to the walls of the chamber said chamber having an outlet through which the products of combustion pass to flow around the chamber to the pipes, a fuel burner discharging into the chamber, a steam pipe leading from the boiler to the said nozzle, a water supply inlet to the boiler, and means

for automatically controlling the said supply inlet.

15. A vapor burner embodying a combustion chamber, a water circulation system embodying a boiler and a pipe system connected therewith, said pipes being disposed outside of and in close proximity to the walls of the chamber, said chamber having an outlet through which the products of combustion pass to flow around the chamber to the pipes, a fuel burner discharging into the chamber, a steam pipe leading from the boiler to the said nozzle, a water supply inlet to the boiler, means for automatically controlling the said supply inlet, an initial heating burner, and a pilot light for igniting the fuel mixture within the combustion chamber. 25
- 10 of combustion pass to flow around the chamber to the pipes, a fuel burner discharging into the chamber, a steam pipe leading from the boiler to the said nozzle, a water supply inlet to the boiler, means 30
- 15 for automatically controlling the said supply inlet, and an initial heating burner disposed to direct the products of combustion therefrom against the pipes and exterior of the said combustion chamber. 35
- 20 16. A vapor burner embodying a com-

bustion chamber, a water circulation system embodying a boiler and a pipe system connected therewith, said pipes being disposed outside of and in close proximity to the walls of the chamber, said chamber having an outlet through which the products of combustion pass to flow around the chamber to the pipes, a fuel burner discharging into the chamber, a steam pipe leading from the boiler to the said nozzle, a water supply inlet to the boiler, means for automatically controlling the said supply inlet, an initial heating burner, and a pilot light for igniting the fuel mixture within the combustion chamber.

In testimony whereof they have signed their names to this specification, on this 18th day of Aug., A. D. 1922.

ALFRED D. ANTOINE.
ALBERT E. GEBERT.
